UNITED STATES PATENT OFFICE.

CHARLES W. HAWTHORNE, OF BUFFALO, NEW YORK, ASSIGNOR TO UNITED ENGINEERING & FOUNDRY COMPANY, OF PITTSBURGH, PENNSYLVANIA, A CORPORATION OF PENNSYLVANIA.

COOLING MECHANISM FOR ROLLING-MILL ROLLS.

1,234,899.

Specification of Letters Patent. Patented July 31, 1917.

Application filed March 17, 1917. Serial No. 155,429.

To all whom it may concern:

Be it known that I, CHARLES W. HAWTHORNE, a citizen of the United States, residing at Buffalo, Erie county, New York, have invented a new and useful Cooling Mechanism for Rolling-Mill Rolls, of which the following is a full, clear, and exact description, reference being had to the accompanying drawings, forming part of this specification, in which:

Figure 1 is a view partly in top plan and partly in horizontal section of a portion of a rolling mill having my invention applied thereto.

Fig. 2 is a section on the irregular line II—II of Fig. 1.

Fig. 3 is a sectional elevation showing one form of governor controlled valve.

Fig. 4 is a detail sectional view showing one of the single-acting clutches.

Fig. 5 is a section on the line V—V of Fig. 1, and

Fig. 6 is a view taken on the general plane of the line VI—VI of Fig. 1, but showing a modified form of the governor controlled valves.

My invention has relation to mechanism for cooling rolling mill rolls; and is designed to provide simple and effective mechanism of this character which will be economical in its use of water, the cooling water being directed only upon the particular pass of the rolls being used at any particular time. My invention also provides mechanism of this character in which the cooling jets may be shifted from one roll pass to another simultaneously with the movement of the movable table guides. It also provides a cooling mechanism in which the supply of water will be automatically shut off except at such times as the rolls are in operation.

The nature of my invention will be best understood by reference to the accompanying drawings, in which I have shown the preferred embodiment thereof, and which will now be described, it being premised, however, that various changes may be made in the details of construction and arrangement and combination of the parts within the spirit and scope of my invention as defined in the appended claims.

In these drawings the numerals 2 and 3 designate the top and bottom rolls of a two-

high rolling mill. 4 designates the table rolls at one side of the mill, and 5 the similar table rolls at the opposite side of the mill rolls. 6 and 7 designate the movable table guides, which are shown as being actuated by hydraulic cylinders 8 to which they are suitably connected. 9 is the driving spindle for the mill rolls.

The parts as thus far described may be of any usual or well known character, and in themselves form no part of my present invention.

In accordance with my invention I mount one or more water discharge pipes 10 upon each of the movable table guides 6 and 7, each of these pipes having a connecting pipe 11 leading into a telescope casing or cylinder 12 which may be conveniently mounted on the supports for the actuating cylinders 8. Each of the casings or cylinders 12 has a supply connection 13 with a common water supply pipe 14. In the particular arrangement which I have illustrated I have shown each of the table guides 6 and 7 as having two of the pipes 10, one of them being mounted above the table rolls, and the other below said rolls, each of these pipes terminating in a bent nozzle portion which is adapted to direct its discharge against one of the passes of the rolls. As the guides are shifted from one pass to another the pipes 10 will be correspondingly shifted, the connections 11 telescoping in the casings or cylinders 12. In this manner the cooling water will always be properly directed upon the particular roll pass which is being used.

In order to reduce the amount of water required and to prevent waste thereof, it is desirable that some means be provided for automatically cutting off the supply of water to the pipes 10 when the mill rolls are not turning. For this purpose I have shown each of the supply connections 13 as having therein a controlling valve 15 (see Fig. 3). The stem 16 of each of these valves is provided with a centrifugal ball governor 17. The sleeve 18 of this governor is shown as being driven by bevel gears 19 from a shaft 20 having a pulley 21 connected by a belt 22 with the driving spindle 9.

It will be seen that the valve 15 is held closed by the governor when the latter is idle; but when the spindle 19 is running at its driving speed, the outward movement of

the governor balls will force the valve stem 16 downwardly sufficiently to open the valve 15. The supply of water therefore will commence as soon as the rolls reach their normal driving speed and will be automatically shut off as soon as the rolls are stopped.

It is also desirable that only those pipes 10 at the entering side of the rolls shall be in operation at any given time. I therefore provide means by which the water will automatically be supplied to the pipes 10 at the entering side of the rolls, and will be automatically shut off from the corresponding pipes at the opposite side each time the direction of rotation of the rolls is reversed. This may be conveniently effected by providing single-acting clutches 23 (see Fig. 4) in the connections between the pulley 21 and the bevel gears 19. These two clutches are set to operate in reverse directions, and in such proper direction that the water will be automatically cut off from the pipes at one side of the rolls and supplied to those at the other side at each reversal of the mill.

The advantages of my invention will be apparent to those familiar with this art, since it provides a very simple and effective means for furnishing the particular mill pass being used with an adequate supply of cooling water, concentrated at that particular pass, and at the entering side thereof. The provisions for automatically controlling the supply when the mill is started and stopped, and for automatically reversing the supply from one side to the other as the mill is reversed enables the cooling to be effected with a minimum amount of water and with but little waste.

In the modification shown in Fig. 6 the governors 17^a instead of acting directly upon the water controlling valves 15^a, operate movable contact members 24, which co-operate with fixed contact members 24^a to open and close an electric circuit 25. This circuit includes therein the coil or winding 26 of an electromagnet of the solenoid type, the movable core of this magnet being extended to form the stem of the valve 15^a. When the governor 17^a is idle the contacts 24 and 24^a are separated, thus deenergizing the magnet 26 and holding the valve 15^a closed. As the rolls speed up the governor closes the circuit at the contacts 24 and 24^a, energizing magnet 26 and thereby opening valve 15^a.

I desire it to be understood that the means for automatically controlling the valves which are herein shown and described are illustrative only, and that this control may be effected in various other ways within the scope of the appended claims. It will also be obvious that other changes may be made, such as in the number and particular arrangement of the water discharge pipes, their supply connections, and in the means

for automatically shifting the water supply from one side of the rolls to the other, all within the scope of said claims.

I claim:

1. In a rolling mill, the combination with mill rolls, their tables, and movable table guides, of water discharge pipes carried by said guides and movable therewith, and means whereby the supply of water to said pipes is controlled by the mill rolls, substantially as described.

2. In a rolling mill, the combination with mill rolls, and feed tables arranged at opposite sides of said rolls, each of said tables having movable guides, of water discharge pipes carried by said guides and movable therewith, and means for shifting the supply of water from the pipes at one side of the rolls to the pipes at the other side of the rolls when the direction of rotation of the rolls is reversed, substantially as described.

3. In a rolling mill, the combination with mill rolls, feed tables at opposite sides of said rolls, laterally movable guides for each feed table, water supply pipes carried by each of said guides above and below the table rolls and arranged to direct their discharge upon a particular pass of the mill rolls, means for shifting the guides and thereby the said pipes, telescopic supply connections for said pipes, valves for controlling the water supply to said pipes, and governor devices actuated by the driving connections for the rolls for controlling the said valves, substantially as described.

4. In a rolling mill, the combination with mill rolls, feed tables at opposite sides of said rolls, laterally movable guides for each feed table, water supply pipes carried by each of said guides above and below the table rolls and arranged to direct their discharge upon a particular pass of the mill rolls, means for shifting the guides and thereby the said pipes, telescopic supply connections for said pipes, valves for controlling the water supply to said pipes, and governor devices actuated by the driving connections for the rolls for controlling the said valves, together with means whereby the supply of water will be automatically cut off from the pipes at one side of the rolls and delivered to the pipes at the other side of the rolls upon each reversal of the mill, substantially as described.

5. A rolling mill, having water discharge pipes shiftable in a direction lengthwise of the rolls, and means for automatically cutting off the supply of water to said pipes when the rolls are stopped, substantially as described.

6. A rolling mill, having water discharge pipes shiftable in a direction lengthwise of the rolls, and means for automatically supplying water to said pipes when the mill rolls are in action, and for shutting off said

supply when the mill rolls are idle, substantially as described.

7. The combination with the rolls of a rolling mill, of water supply pipes arranged at opposite sides of said rolls and movable in the direction of the length thereof, and means for automatically cutting off the supply of water to the pipes at one side of the rolls for supplying it to the pipes at the

opposite side of the rolls at each reversal of the rolls, substantially as described.

In testimony whereof, I have hereunto set my hand.

CHARLES W. HAWTHORNE.
